UNITED STATES PATENT OFFICE

JEAN LE BLOAS, OF NEW YORK, AND EDWIN STANLEY JANES, OF FLORAL PARK, NEW YORK, ASSIGNORS TO MARCEL GUERLAIN, INC., A CORPORATION OF NEW YORK

DESIGN FOR A BOTTLE OR SIMILAR ARTICLE

Application filed October 15, 1929. Serial No. 33,041. Term of patent 7 years.

To all whom it may concern:

Be it known that we, JEAN LE BLOAS, a citizen of the United States, and a resident of the borough of Manhattan, in the city and State of New York, and EDWIN STANLEY JANES, a citizen of the United States, and a resident of Floral Park, county of Nassau, and State of New York, have invented a new, original, and ornamental Design for a Bottle or Similar Article, of which the following is a specification, reference being had to the accompanying drawing, forming part thereof.

In the said drawing, Fig. 1 is a side view of a bottle or similar article, showing our new design; and Fig. 2 is a top view.

We claim:

The ornamental design for a bottle or similar article, substantially as shown.

In witness whereof we have hereunto signed our names this 7th day of October, 1929.

JEAN LE BLOAS.
EDWIN STANLEY JANES.
